UNITED STATES PATENT OFFICE.

ALLISON H. FLEMING, OF FAIRMONT, WEST VIRGINIA.

RAZOR-STROPPER.

No. 882,630.

Specification of Letters Patent. Patented March 24, 1908.

Application filed December 7, 1907. Serial No. 405,591.

To all whom it may concern:

Be it known that I, ALLISON H. FLEMING, a citizen of the United States, residing at Fairmont, in the county of Marion and 5 State of West Virginia, have invented a new and useful Razor-Stropper, of which the following is a specification.

This invention relates to razor stropers of that general class employed for stropping 10 or honing the blades of safety razors.

The principal object of the invention is to provide a stropper which may be readily adjusted in order to accommodate blades of different size and make, and to permit the 15 exercise of greater or less pressure on the blade during the stropping or honing operation.

With these and other objects in view, as will more fully hereinafter appear, the invention 20 consists in certain novel features of construction and arrangement of parts, hereinafter fully described, illustrated in the accompanying drawings, and particularly pointed out in the appended claims, it being understood that various changes in the form, 25 proportions, size and minor details of the structure may be made without departing from the spirit or sacrificing any of the advantages of the invention.

30 In the accompanying drawings:—Figure 1 is a perspective view of a razor stropper constructed in accordance with the invention. Fig. 2 is a longitudinal sectional view of the same drawn to an enlarged scale. 35 Fig. 3 is a transverse sectional view showing the position of the parts when in use. Fig. 4 is a perspective view of a modified form of shaft.

Similar numerals of reference are employed 40 to indicate corresponding parts throughout the several figures of the drawings.

The present invention is in the nature of an improvement on the construction shown 45 in Letters-Patent of the United States granted to me on August 27, 1907, No. 864,524.

To the carrying or operating handle 10 is secured a strip of metal bent into the form of an angle bar, the two webs of which are arranged 50 at an acute angle to each other, and these webs are rigidly connected near their opposite ends by V-shaped filling blocks 12.

The blocks 12 form bearings for the reception 55 of a rock shaft 15, the reduced ends of which pass through openings in the blocks,

while the major portion of the shaft is rectangular in form, and serves as a support for a razor blade holder. Near the opposite ends of the shaft are small pinions 18 that intermesh with arcuate racks 19. 60

Pivoted to the angle bar 11 is a second angle bar 20, of approximately the same length as the angle bar 11, and the two webs of which are arranged at an obtuse angle to each other, affording sufficient room for the 65 smaller angle bar 11 to play back and forth without coming into contact therewith during the stropping operation.

In pivoting the parts together, the arcuate racks 19 are extended upward through slots 70 21 formed in the inner angle bar 11, and a pivot pin 22 is introduced through openings formed in these racks, and the segmental blocks 12.

The two racks 19 are approximately in the 75 form of quadrants and their ends are rigidly secured to the webs of the angle bars 20, the racks being curved on lines struck from the center of the pivot pin 22, so that the pinions 18 may freely mesh therewith without danger of binding. 80

The rectangular shaft 15 is provided with an elongated slot, which receives a flat angular web 26, that carries a pair of spring jaws 27, that may serve for the reception and support of a razor blade, such, for instance, as a blade having a heavy butt of the type used in the Star or Ever-Ready razors. This web 26 may be adjusted diametrically of the shaft 15, in order to move the edge of the blade 90 which it carries to a greater or less distance beyond the webs of the main angle bar 20, so that the edge of the blade may be presented to the stropping or honing surface at the correct angle, or the extension may be such as to 95 secure greater or less pressure of the blade upon the surface. The web is provided with a pair of slots 28, and these slots permit the passage of binding screws 29 that pass through threaded openings formed in the 100 shaft 15, so that after the web has been adjusted to the proper position, the screws may be tightened for the purpose of securing the web and blade holder in proper position.

As a modification of this construction, the 105 shaft may be formed of two separate members 15^a and 15^b that are slightly spaced from each other to receive the web 26, and after the latter has been adjusted, the screws may be tightened for the purpose of clamping 110

the member 15^a and firmly locking the web in place.

In order to permit the stropping of the thin two edge blades, such, for instance, as those employed in the Gillette type of razor, a. second holder 35 is employed, this holder having pins in one jaw arranged to pass through openings in the razor blade, and, also, to fit in openings formed in the opposite 10 jaw. This auxiliary holder may be readily placed in position in the main holder 27. The angle bar 20 is maintained in contact with the strap, and at the end of each stroke the handle 10 is turned for the purpose of carrying over the angle bar 11; and with it the shaft 15. During this movement the web of the angle bar 20 which was free during the first stroke is moved over into engagement with the strap, and the holder as a 20 whole is swung with the shaft as a center owing to the connection between the pinions and the racks, and the edge of the blade is forced down into contact with the surface of the strap. The edge of the blade comes into 25 contact with the edge of the strap before the angle bar 11 can engage with the angle bar 20, so that the operator is free to exert any desired pressure on the blade during the stropping operation and the stropping may 30 be as light or heavy as the condition of the blade may require.

I claim:—

1. In a razor stroppe, a bar or support having a pair of angularly related surfaces arranged for contact with the strap, a pivotally mounted shaft arranged in the support, a blade carrier, and means for adjustably securing the blade carrier to said shaft. 35
2. In a razor stroppe, a bar or support having a pair of angularly related surfaces arranged for contact with the strap, a pivotally mounted shaft carried by said support, a blade holder adjustable in a radial line toward and from the axis of said shaft, and means for locking said blade holder in ad- 40 justed position. 45
3. In a razor stroppe, a bar or support having a pair of angularly related surfaces arranged for contact with the strap, a pivotally mounted shaft arranged in said support 50 and provided with a diametrical slot, a blade carrier, and an elongated web forming a support for the carrier and adjustably mounted within the slot, and locking screws for clamping the shaft and web together. 55

In testimony that I claim the foregoing as my own, I have hereto affixed my signature in the presence of two witnesses.

ALLISON H. FLEMING.
